2,001,485

SPILLAGE DEVICE FOR BAG FILLING
MACHINES

Austin S. Chandler, Fitchburg, Mass., assignor
to The Brown Bag Filling Machine Company,
Fitchburg, Mass., a corporation of Massachusetts

Application October 3, 1934, Serial No. 746,733

7 Claims. (Cl. 226—49)

The invention relates to devices for bag and other receptacle filling machines, and has for a purpose to present a new and simple device for use in conjunction with a charge measuring and delivering means and a receptacle-presenting means whereby, in case a receptacle is not properly presented, or does not become set in proper receiving relation to the charge delivering means the charge will be guided to a proper point of storage, or returned to the stock in the machine. It is particularly useful where a charge delivering device is employed to discharge or throw a charge in a path which includes the position in which the empty receptacle should be set properly, one device of this kind being illustrated in my co-pending application, Ser. No. 668,048, filed September 2, 1933, for Receptacle filling and sealing machines; and my present invention will be useful whether an intervening tunnel is used to guide the charge, or whether the latter is thrown or directed into the receptacle without any intervening tube. It is an aim to present a device for returning a charge when a receptacle is presented but not opened fully enough to receive the charge, and which will respond to engagement of the receptacle itself when properly opened, to permit entry of the charge thereto.

It is also an aim to construct the appliance in such manner that it will be inexpensive, light in weight, will occupy small space in the filling machine, and will not require power connections for its operation; yet which will be highly effective and durable in operation with a minimum liability of derangement.

Additional objects, advantages, and features of invention reside in the construction, arrangement and combination of parts involved in the embodiment of the invention, as will appear from the following description and accompanying drawings, wherein

Figure 1 is an end view of the machine of my said prior application with non-essential parts omitted and a part of the hopper wall broken away to show the measure.

Figure 2 is a fragmentary elevation of the bag opener and hopper with parts broken away to show the funnel, trap, and return chute.

Figure 3 is an enlarged vertical sectional view of the spillage device at initial position of the bag opener, taken on the line 3—3 of Figure 2.

Figure 4 is a similar view showing the opener operated and no bag properly presented.

Figure 5 is a similar view showing a bag properly opened and engaging the spiller.

Figure 6 is a horizontal section on the line 6—6 of Fig. 5.

The prior machine on which my invention is shown included a hopper 10 having a stock conveyor lift 30, a top hopper 31, and a measuring device 33 operative as described in my prior patent application. There was also provided a bag presenting device 85—91 operative as described in the said patent application, in conjunction with the endless ribbed belt conveyor 105. The details of these mechanisms being no novel part of the present invention, are not described in detail here.

Bags 87 are shown in the box or chute 85, which are brought into position to receive the lower end of the opener 63 mounted for vertical reciprocation on the front side of the hopper 10. This opener, as described in my prior application, is of thin sheet metal, U-shaped in cross section including a planiform front wall or plate 11 having a lower projecting arcuate edge 12, and side walls 13 at right angles thereto, their rear or outer edges 14 having a maximum horizontal projection at their upper portions, and being gradually decreased in extent toward their lower ends where they merge into the plate 11. In other words, their edges are inclined outwardly and upwardly from the plane of the plate 11 for the major part of their vertical extent, so that after the projecting lower edge 12 of the opener enters a bag, the inclined edges 14 of the walls 13 will engage the back wall of the bag and press it rearwardly from the front wall, opening the bag sufficiently to receive a charge from the measure 33. The opener 63 is reciprocated by any suitable means in coordination with the measure, as is understood.

For guiding the charge from the measure 33 to the bag when presented and opened, a charge guide hopper or chute 15 is formed in a forward extension 16 of the front of the main hopper 10 which is projected over the conveyor 105, stopping short of and being formed with a vertical wall adjacent the plane of the first bag in the bag box 85 when presented in position for opening. This forward extension of the hopper 10 has a lower side or floor 17 extending rearwardly from the mouth of the chute 15 and located some distance above the level of the top of a bag of maximum height that may be presented. To accommodate shorter bags removable spout pieces 18 are provided, one of which is removably attached to the lower side 17 of the hopper extension 16, and its sides alined with those of the chute 15, so as to form a continuous passage through the parts 55

15 and 18. This passage may be of nearly or quite uniform width from side to side but from front to back is preferably tapered downwardly, as shown. The spout projects clear of adjacent structural parts, and has pivoted on a lug 19 at its rear upper part a diverter or trap 20. This trap consists of two arms 21 pivoted at respective sides of the spout on the lug 19, and carrying at their lower ends a chute-like charge guiding or deflecting part consisting of an inclined plate 22 having side plates 23 joined with the arms 21. The inclined plate extends upwardly and forwardly so that it may rest snugly against the front lower edge of the spout 18, while the side plates 23 abut the lower side edges of the spout 18. Small contractile springs 24 are connected between the arms and the spout to hold the trap snugly at the bottom of the spout, but yieldable to pressure of an opened bag thereagainst. The trap or diverter 18 is made preferably of the lightest materials and of limited dimensions so that the mass required to be moved by the bag will be a minimum. The inclined plate 22 is preferably at an angle not less than 45 degrees to the horizontal, and is extended rearwardly from its upper edge beyond the space required to accommodate a filled bag before the bag box 85. But the space under the upper forward extension 16 of the main hopper 10 extends further toward the rear, and the front side of the hopper 10 is open on this space as at 21 from immediately under the top floor 17 to a distance a little above the level of the bottom of the bag box, where a lower slight forward projection or mouth 22 of the hopper is formed open only at the upper side. Its front side is vertical for a short distance, and from this there extends downwardly and rearwardly the inclined bottom 23 of the hopper 10. A receiver or guide 24 of diverted charges is provided below the trap, which is substantially U-shaped in cross section, having the inclined bottom plate 25, the lower part of which is turned downward to set in the mouth 22, and the parallel vertical side plates 26 integral with the bottom 25 the upper forward parts of which are formed with vertical edges between which the trap 20 swings freely. The plate 25 preferably extends upwardly above the level of the lower edge of the trap when the latter is in initial position as in Figures 1, 3 and 4, and engages that edge of the trap as a stop, as in Figures 3 and 4. The front opening 21 of the hopper 10 is narrower than the hopper 10 and the latter has flanges 27 (Fig. 2) extending vertically beside the opening, forming part of the body of the hopper 10. The side plates 26 of the receiver are formed with lateral flanges 28 secured removably to the flanges 27. The guide 24 is shown with a back wall 29, which may have an upper part curved forwardly as desired, and will prevent stock spilling from the measure from escaping through the opening 21, although the wall 28 may be omitted and other guard means provided. It will be noted that the opener 63 is vertically slidable on the front part of the extension 16, the side plates of the opener fitting loosely and slidably beside the sides of the extension. The chute 15, spout 18 and the trap 20 are narrower. The plates 32 of the lower guide chute 28 are also spaced to lie within and clear of the side plates 13 of the opener 63. The rear part of the trap lies initially between the forward upper parts of the plates 32, and swings freely therebetween. These parts including the opener 63 may be used for various widths of bags, but it may be

found desirable to use a wider opener for wider bags, so that when opened the rearwardly pressed back wall of a bag will have sufficient tension to press the trap 20 rearwardly. If shorter bags are used than shown, it is desirable to use a spout 18 longer than shown, with the trap 20 correspondingly lower, and in consequence a corresponding guide 28 with its plate 29 stopping properly will also be essential.

In use, the bag box 85 is supplied with flat paper bags each having a rear wall 40 and a front wall 41 having a tongue 42 projected above the top edge of the wall 40. The mechanism of the machine moves the box rearwardly until the tongue of the first bag bears against the tongue 12 of the opener 63, while the wall 40 passes under the tongue of the opener, and by the resilience of the bags is caused to become slightly spaced from the front wall of the bag. The mechanism then operates the opener which is plunged downward, the edges 14 of the side plates 13 of the opener pressing against the top edge portion of the wall 40 of the bag and moving it rearwardly until the opener is fully engaged in the bag. In this movement of the wall 40 of the bag it engages the plate 22 of the trap 20, and causes the latter to swing rearwardly from under the spout 18, until the wall 40 of the bag is located to the rear of the spout, as in Figure 5. The mechanism of the machine will then already have initiated movement of the measure 33 forwardly, and upon completion of that movement the contents of the measure will be projected or catapulted into the guide 15, through the spout 18 into the bag. The box 85 will then be drawn forwardly, permitting the bag to drop on the conveyor 105 by which it will be removed and the filling operations repeated as described. In the event that no bag is presented by the box 85, or should the opener 63 engage improperly and cause collapse of the engaged bag, there will be no wall 40 stretched across the rear and outer edges 14 of the side walls 13 of the opener, and the trap will remain in position as shown in Figures 3 and 4. The charge thrown from the measure will then be guided by the trap rearwardly into the guide 28 from which it passes into the hopper 10.

It will be seen that the side plates 13 in fixed spaced relation are the essential opening means for the bag, the plate 11 serving principally as a spacing means as far as the opening operation is concerned, although in the particular apparatus of the machine illustrated it also serves to support the bag in conjunction with the box 85, until the latter is drawn forwardly, relieving the filled bag from frictional engagement with the next bag in the box.

I claim:

1. A charge spiller for bag filling machines and the like comprising a charge delivering means, a bag presenting means to move part of an open bag into receiving relation thereto, a charge diverter movable into receiving relation to the charge delivering means, yielding means to hold the diverter in receiving position, said diverter being located in the path of a bag part to receiving position, whereby the diverter will be moved out of receiving position by such bag.

2. The structure of claim 1 in which the charge delivering means includes a bag opener including two spaced apart members adapted to enter a bag and to stretch the same to draw an advancing wall of the bag sufficiently taut to move the diverter.

3. The structure of claim 1 in which the charge

delivering means includes a delivery spout, the diverter device being in the form of a chute-like member having an open upper part initially in receiving relation to the spout, and being pivoted 5 to swing laterally from receiving position, away from the spout and a presented bag.

4. The structure of claim 1 in which the charge delivering means includes a delivery spout, the diverter device being in the form of a chute-like 10 member having an open upper part initially in receiving relation to the spout, and being pivoted to swing laterally from receiving position away from the spout and a presented bag, and a spring 15 connected with the diverter and anchored under stress tending to hold the diverter in receiving 20 position.

5. The structure of claim 1 in which the charge delivering means includes a delivery spout, the diverter device being in the form of a chute-like 25 member having an open upper part initially in receiving relation to the spout, and being pivoted to swing laterally from receiving position, away from the spout and a presented bag, the bag-presenting means being constructed to open a bag and to present the open part of the bag closely 30 beneath the spout and against the diverter, with the advanced wall of the bag unsupported at its mouth over a part extending beyond the diverter at each side, but sufficiently taut to move the diverter.

6. In a bag of the character described, means to deliver a charge for bags, means to present a bag adjacent the path of delivery of the charge, an opener comprising two spaced apart tapered members adapted to enter the presented bag and move the outer side thereof across said path, a diverter movable into and out of said path, and having a part in the path of the said outer wall of a presented bag when opened, and yielding means to hold the diverter in the path yieldable 10 to said wall of a bag. 5

7. In a machine of the character described, a main hopper having an upper forwardly extended part having an opening through its lower side, means to project a charge therethrough, means to 15 present a bag in line closely adjacent the front side of the extension, an opener on the extension movable to enter the bag and having two wall spreading members inclined upward from the plane of entrance to the bag in a plane extending across 20 said path and constructed, arranged and adapted to move the wall of the bag next said path across the path to receive a charge therewithin, a charge diverter movable to receive a charge through said opening and movable out of said path, and being 25 in the path of movement of a wall moved by the wall spreading members, and means to hold the diverter in receiving position yieldable to the wall of a bag. 25

AUSTIN S. CHANDLER. 30
